UNITED STATES PATENT OFFICE.

CHARLES L. EIDLITZ, OF NEW YORK, N. Y., ASSIGNOR TO METROPOLITAN ELECTRIC MANUFACTURING COMPANY, A CORPORATION OF NEW JERSEY.

SAFETY SWITCH AND FUSE BOX.

1,417,723.

Specification of Letters Patent. Patented May 30, 1922.

Application filed August 14, 1919. Serial No. 317,515.

To all whom it may concern:

Be it known that I, CHARLES L. EIDLITZ, a citizen of the United States, residing at the city of New York, in the borough of Manhattan and State of New York, have invented certain new and useful Improvements in Safety Switch and Fuse Boxes, of which the following is a full, clear, and exact description.

10 My invention relates to safety switch and fuse boxes and particularly to those using a rotary snap switch.

An object of my invention is to provide a device of this kind which will prevent the 15 door of the box from being opened until, and only when, the switch is in "off" position, and prevent closing of the door except when the switch is in "off" position.

20 A further object is to provide a device of this character which is simple and reliable, and of low cost of production.

Other objects will appear as the description proceeds.

The invention comprises among other 25 things, the provision of a slot in the cover of the box through which the operating button of the switch passes, the slot being non-circular with a portion of less radius than the greatest radius of the button or being otherwise so shaped that the cover can only be moved to open or closed position when the button and slot register, which registry can only occur when the switch is in "off" 30 position. It may also, if desired, be utilized in connection with a slotted member rotating 35 with the switch button and cooperating with a part carried by the cover to lock the switch against actuation when the cover is in open position and permit such operation when 40 the cover is in closed position. In the drawings:

Fig. 1. is a plan view of one embodiment 45 of my invention, the cover being shown in opened position and the switch in "off" position:

Fig. 2 is also a plan view, but with the cover in closed position, the locking disc on the switch and the tongue on the cover being shown in dotted lines:

50 Fig. 3 is a view similar to Fig. 2, but with the switch shown in a different position;

Fig. 4 is a partial side view of the device with the cover in raised or opened position;

55 Fig. 5 is a view similar to Fig. 4, but with the cover in closed position;

Fig. 6 shows the catch in detail and detached from the box.

The switch and fuse plugs are carried in a casing 1, having a cover 2 hinged thereto by any suitable means as at 3. The cover 60 is held in closed position by a catch 4, shown in detail in Fig. 6. The catch 4, which is fastened to the box in any suitable manner as by rivets 5, passes through a slot 6 in the cover and engages and holds the cover closed 65 by means of struck out portions 7, the resiliency of the catch causing it to normally hold the cover closed and permitting it to yield to release the cover. The catch has a hole 8 in its upper or projecting end, to accommodate locking means, if desired.

The switch 9 is of the rotary snap type and is preferably also of the double pole type, having the double cross contact arms in different planes. The switch is carried 75 on an insulating base 10, which also carries the binding posts 11, 12, 13 and 14, and fuse plugs 15. The wires entering the box are connected to binding posts 13 and 14, and the wires leaving the box are connected to binding posts 11 and 12. The fuse plugs 15 are shown here as of the self contained or protected type, but may be of any suitable kind, and connect binding posts 11 and 12 with the switch poles by means of contacts 16 and 80 17, the other switch poles being connected to binding posts 13 and 14. The fuse plugs are held in place yieldingly by the spring clips 18, thus permitting ready removal or renewal.

The switch stem 19 carries the usual operating button 20, held thereon by a screw 21, and the stem has a bearing at its upper end in the flat traverse bar 22, held within and across the box by screws 23. The cover 2 has a slot 24 therein, which is similar in shape to, but slightly larger than the button, with a portion of less radius from the axis of rotation of the button than the outermost part of the button and which is so placed in the cover that the button passes through it when the cover is moved to open or closed positions with the switch off and prevents passage of the button and thereby movement of the cover to open position 105 whenever the switch is in "on" position.

The stem also carries thereon a locking disc 25 having two diametrically opposed slots 26 in its periphery, the diametrical axis connecting the slots being in the same verti- 110

cal plane with that of the major length of the button, as shown in Figs. 1 and 2 for example. The cover 2 carries a locking tongue 27 on its underside, adapted to contact with the disc 25 and slots 26. The tongue 27 is so shaped and placed on the cover, that when the cover is in closed position (Fig. 5) the tongue is clear of the slot 26 in the disc 25 and the switch can be freely operated. As soon as the cover is slightly raised, the corner 28 of the tongue engages in the slot and locks the switch in "off" position if the switch is in that position and if the switch is not in "off" position, neither of the slots will be in register with the tongue, and the corner 28 will engage under the disc and prevent further opening of the cover. When the switch is in the "off" position with one of the slots registering with the tongue, and the cover is raised, the corner 29 will engage against the rear wall of the box and limit the opening movement of the cover, and the tongue will, during the opening movement, remain within the slot and lock the switch against movement while the cover remains opened for any substantial distance.

Assuming the device with the cover closed, as in Fig. 5, the button 20 can be manipulated at will to open and close the switch. The slot 24 being of a shape similar to the button 20 prevents the opening of the cover until the switch is in "off" position, since the button and slot only register and permit of an opening movement of the cover when the switch is in this position. The cover can be opened when desired for the purpose of inspection, or the renewal of fuses, solely when the switch is in "off" position where-
40 by danger of shock by one forgetting to first turn the switch to "off" position is avoided. In the embodiment illustrated, disc 25 will also lock the cover against opening until the switch has been placed in "off" position, as shown in Figs. 1, 2 and 4, for example. The cover can then be opened and immediately, through entry of tongue 27 into one of the slots 26, the switch is locked against further actuation until the cover is again closed.
50 It will thus be seen that since the switch must of necessity always be in the "off" position whenever the cover is not closed, there is no danger of electrical shock to the person renewing fuses or working in the box.

55 I claim:

1. In a safety switch and fuse box, the combination of a casing and a cover therefor, a switch within the casing and having

an operating member projecting through the cover when the cover is in closed position, 60 the member and opening through which it projects being so shaped as to permit the cover to be opened when the member is in certain positions and prevent it when in all other positions.

2. In a safety switch and fuse box the combination of a casing, and a hinged cover therefor, a switch within the casing and having a rotary operating member projecting through the cover when the cover is in closed 70 position, the member and opening through which it projects being so shaped as to permit the cover to be opened when the member is in certain positions, and prevent it when the member is in all other positions. 75

3. In a safety switch and fuse box, a casing, a rotary switch within the casing having an operating member with a non-circular operating button, a cover for the casing having an aperture therein through which 80 the member projects when the cover is in closed position, the aperture permitting passage therethrough of the button when in one relative position, during a movement of the cover, a portion of the edge of the aperture being at a lesser distance from the axis of rotation of the member than the extreme outermost part of the periphery of the button, but at a greater distance therefrom than the innermost part of the periphery of the 90 button, whereby the aperture will prevent the passage of the button therethrough when in other relative positions and thus lock the cover closed.

4. In a safety switch and fuse box, a cas- 95 ing, a rotary switch within the casing having an operating member with a non-circular operating button, a cover for the casing having an aperture therein through which the member projects when the cover is in 100 closed position, the aperture having a shape similar to but slightly larger than the button with which the button is aligned when the switch is in "off" position so as to permit passage therethrough of the button during an opening movement of the cover, and prevent such passage and consequent opening of the cover when the button and aperture are out of alignment and the switch is in "on" position.

In witness whereof, I subscribe my signature, in the presence of two witnesses.

CHAS. L. EIDLITZ.
